UNITED STATES PATENT OFFICE.

NAT DENSLER, OF BOWIE, TEXAS.

PROJECTILE.

SPECIFICATION forming part of Letters Patent No. 723,249, dated March 24, 1903.

Application filed May 27, 1902. Serial No. 109,212. (No model.)

To all whom it may concern:

Be it known that I, NAT DENSLER, a citizen of the United States, residing at Bowie, in the county of Montague and State of Texas, 5 have invented a new and useful Projectile, of which the following is a specification.

This invention relates to certain improvements in projectiles, and has for its principal object to provide an improved form of armor-piercing shell adapted to contain a quantity of high explosive, which is positively set off at any desired point after the projectile has passed through the armor and without the employment of time-fuses or the similar igniting devices ordinarily relied upon for this purpose.

With this and other objects in view the invention consists in the novel construction and arrangement of parts hereinafter described, 20 illustrated in the accompanying drawings, and particularly pointed out in the appended claims.

In the drawings, Figure 1 is a longitudinal sectional elevation of a projectile constructed in accordance with my invention. Fig. 2 is a view illustrating the projectile-casing stripped from the main body of the projectile after the latter has passed through an armor-plate.

30 The main body of the projectile is approximately cylindrical in form and provided with a pointed front end 10, which may be covered with lead, graphite, or the like. The central portion of the projectile is filled with an explosive compound 11, such compound being formed of any desired material and arranged within a chamber formed in the body of the projectile, although the arrangement of the projectile may be that ordinarily followed 35 and the explosive material surrounded by a large number of balls or blocks, which will be scattered on the explosion of the shell. After the shell is filled the filling-opening is closed by a nut 12, having on its inner face 40 an annular flange forming a cup-like recess for the reception of a fulminic or other detonator 14. The nut is provided with a central opening, through which extends a firing-pin 15, having at its inner end a disk 16, adapted 45 to be moved forcibly against the detonator and cause the explosion of the compound 11 at the desired time. Normally the disk 16 is

held out of contact with the detonator by means of a helical compression-spring 17, surrounding a portion of the firing-pin and extending between an annular flange 18 on the latter and a shoulder formed in the nut 12. 55

The projectile proper is surrounded by a metallic casing 19, which extends over the rear end of the projectile and around the periphery thereof to a point at the base of the conical or pointed front end of the projectile. At the juncture of the pointed end and the body of the projectile the diameter of the latter is somewhat greater than the main 60 body portion, thus forming an annular flange 20, over which fits the correspondingly-shaped forward end of the casing 19, and the extreme end of said casing is bent or crimped inwardly over the base portion of the conical 65 end in order to firmly hold said casing in place during handling, loading, and firing. To the rear end of the casing is secured an eyebolt 21, which is connected to an eye on the end of the firing-pin by means of a wire 70 22, said wire being coiled in an open space between the rear end of the nut 12 and the casing. 75

Owing to the presence of the spring 17, which holds the disk away from the detonator, 80 the projectile may be handled with safety and may be loaded and fired in the usual manner. When the projectile strikes an armor-plate, an opening is formed therein, the walls of the opening being bent to the rear 85 and binding firmly on the casing 19, retaining said casing during the continued movement of the main body of the projectile. The point where greatest pressure is exercised will be on the thinner portions of the 90 casing which surround the flange 20, so that when the latter is once free from the casing there will be no tendency to bind on the smaller diameter of the main body of the projectile, and the latter continues to a point 95 beyond the armor-plate, while the casing remains in the opening formed by the projectile. When the projectile has reached a certain point beyond the armor, depending upon the length of the wire 22, the firing-pin is held 100 stationary, and the further forward movement of the projectile causes the disk 16 to come into contact with the fulminate and explode the charge.

Where the armor is thin, as on torpedo-boats and the like, there is danger of the projectile passing through the armor as an entirety, and to avoid this I sometimes make the casing much thicker in order to offer greater resistance and insure the stripping of the casing from the projectile. Thus, for instance, the casing may be of the thickness indicated by dotted lines in Fig. 1 or of any other thickness which may be found best in practice.

The construction is such as to positively insure the explosion of the projectile at any desired point and the action is more reliable than is the case with time-fuses, where exact results cannot be insured, or with impact-projectiles, which explode when they come into contact with the armor.

It is to be understood that various changes in the construction of the projectile may be made without departing from the spirit of the invention, which resides, broadly, in the use of a sectional projectile whose members are separated during the passage of the projectile through armor or its equivalent to thereby insure the explosion of a compound carried by said projectile.

Having thus described the invention, what I claim is—

30 1. A sectional projectile of which the sections are adapted to separate during the passage of the projectile through a resisting material, an explosive compound carried by said projectile, and means connecting the sections to insure the explosion of said compound.

25 2. A projectile comprising a body portion having an explosive compound therein, a casing surrounding the body portion and adapted to be engaged and held by a resisting material during the passage of the projectile therethrough, and means connecting the body portion to the casing to insure the explosion of said compound.

35 3. The combination in a projectile, of the body portion having a forward pointed end and provided with an enlarged flange at the base of the pointed portion, an explosive com-

50 pound carried by said body portion, a casing partly surrounding the body portion and flange and having its front edge bent inwardly over the base of the pointed end, and means for connecting the body portion to the casing to insure the explosion of said compound.

4. The combination in a projectile, of the body portion, having a central chamber for the reception of an explosive compound, a threaded opening leading to said chamber, a nut for closing said opening and provided with a central pin-guiding opening, a firing pin guided in the opening, a detonator arranged within the chamber, a spring surrounding the firing-pin and tending to hold the latter in inoperative position, a separable casing partly surrounding the body portion 65 of the projectile, and a flexible connecting device extending between said casing and the firing-pin.

5. The combination in a projectile, of the body portion having a central chamber for 70 the reception of an explosive compound, a threaded opening leading to said chamber, a nut for closing said opening and provided with a central pin-guiding opening, an annular flange disposed on the inner face of the 75 nut and forming a cup-like chamber for the reception of a detonator, a firing-pin guided in the nut-opening and having at its inner end a disk for engaging the detonator, a spring surrounding the firing-pin and normally tending to hold the disk away from said detonator, a removable casing surrounding a portion of the projectile, an eyebolt carried by said casing, and a wire connecting said eyebolt to the end of the firing-pin, substantially as specified.

In testimony that I claim the foregoing as my own I have hereto affixed my signature in the presence of two witnesses.

NAT DENSLER.
